UNITED STATES PATENT OFFICE.

RAY D. STREBY, OF CANTON, OHIO, ASSIGNOR TO THE TIMKEN ROLLER BEARING COMPANY, OF CANTON, OHIO, A CORPORATION OF OHIO.

GROOVE-DRESSING TOOL.

Application filed October 31, 1927. Serial No. 229,876.

My invention relates to tools for dressing or grinding the walls of grooves, more particularly tools for dressing or grinding the bottom of the helical groove of a feed wheel 5 or cylinder such as the feed wheel of a centerless grinding machine. It has for its principal objects means for easily and accurately dressing or grinding the bottoms of such helical grooves and for easily accommodating 10 the nice adjustments required in such a device.

The invention consists principally in a grinding wheel adapted to be set to conform to the lead of a helical groove and mounted 15 on a slideable hanger that is provided with means engaging a side wall of a groove, whereby the grinding wheel may be fed along the groove by rotating the feed wheel or other member whose groove is being dressed. The 20 invention further consists in the groove dressing tool and in the parts and combinations and arrangements of parts hereinafter described and claimed.

In the accompanying drawing, wherein 25 like reference numerals refer to like parts wherever they occur,

Fig. 1 is a side elevation of a grinding machine feed wheel having a helical groove and a groove dressing tool therefor embodying 30 my invention.

Fig. 2 is a vertical sectional view on the line 2—2 of Fig. 1, certain parts appearing in elevation,

Fig. 3 is a vertical sectional view,

Fig. 4 is an elevation of a portion of the mechanism looking in the direction of the arrows 4—4 in Fig. 3,

Fig. 5 is a detail view of the guide that controls the movement of the grinding wheel,

Fig. 6 is a detail sectional view on the line 40 6—6 of Fig. 5,

Fig. 7 is a cross-sectional view through the main slide member and the gib that supports the same,

Fig. 8 is a fragmentary sectional view on the line 8—8 of Fig. 9,

Fig. 9 is a sectional view on the line 9—9 of Fig. 7; and

Fig. 10 is a cross-sectional view on the line 50 10—10 of Fig. 3.

The accompanying drawing shows my invention embodied in a tool for dressing the bottom of the helical feed groove 1 in the feed wheel 2 of a centerless grinding machine, such 55 as is used, for instance, in grinding conical

rollers for roller bearings. Secured to a portion 3 of the frame of the machine near the feed wheel, as by bolts 4, is a gib 5 on which is mounted a slide 6. Said slide 6 is undercut along one edge 7 to receive one beveled 60 edge of the gib and in a recess along the other edge is disposed an adjustable gib 8 having an inclined surface 9 cooperating with the other edge of the gib. Screws 10 extend through vertically elongated holes 11 in said gib 8 and are threaded into said slide 6. Lock screws 12 mounted in the top of said slide 6 bear against the top of said adjustable gib 8 to locate it vertically

Said slide 6 is provided with a circular recess in which is mounted a circular hub portion 13 of a head 14. A screw 15 having an enlarged flat head 16 is mounted in a recess in the back face of said slide and is threaded into said hub portion 13 of said head 14. Thus 70 said head 14 may be turned in said slide and may be secured in desired position by means of screws 17 extending through arcuate slots 18 in said head 14 and threaded into holes in said slide 6. Around its periphery the hub 13 80 may be provided with an annular rib 19 that extends into a countersunk annular recess 20 provided therefor in said head. Said slide 6 may be provided with a hole 21 in whose inner end is a plug 22 that engages the peripheral rib 19 of said hub 13. A screw 23 threaded into the outer end of said hole 21 engages said plug 22, said plug 22 and screw 23 constitute an additional means for holding said head 14 in the desired angular position. 85

Said head 14 is provided with undercut jaw members 24 constituting slideways in which is mounted a slide member 25. Said slide 25 extends transversely with respect to said main slide 6. Said head 14 is provided with a cross member 26 disposed in line with the end of said slide member and provided with an opening through which extends a pin 27 that is provided with a handle 28 that abuts against the cross member. On the other side 90 of the cross member 26 from the handle 28 is an annular rib 29 on said pin 27 and a washer 30 is interposed between said rib 29 and the cross member 26. Said pin 27 is provided with a threaded portion 31 extending into a threaded hole 32 provided therefor in the slide member 25 that is mounted in said slideways. By turning said handle 28 and pin 27, said slide member 25 may be raised or lowered. Said slide member 25 has an angularly 100 105 110

projecting portion 33 to which is secured as by a cap 34 and a screw 35, a yoke 36 having guide portions 37 adapted to extend into adjacent twists of the helical groove of the feed wheel and engage the walls of said groove. 5 Obviously by turning said handle 28 and pin 27, said slide 25 that serves as a carrier for said guide 37 may be raised and lowered to accommodate the guides to feed wheels of different diameters and to cause the guides to be engaged with and disengaged from the work. 10 Said slide or guide carrier 25 is provided with undercut portions 38 providing slide-ways for an undercut groove in a slide member 39 that carries a grinding wheel 40. The grinding wheel carrier 39 is provided with a substantially semicircular journal bearing portion 41 to which is secured as by screws 20 42 a cooperating semicircular portion 43. Through the circular opening thus formed extends a shaft 44 on the end of which is secured, as by a screw 45, the grinding wheel 40 that grinds the bottom of said groove. 25 Said grinding wheel carrier 39 has an end piece 46 that is provided with a slot 47 in one projecting portion through which extends the reduced neck portion of a screw 48 that extends into a threaded hole 49 provided therefor in the guide carrier 25. Thus by 30 turning said screw 48, said grinding wheel carrier 39 may be moved in and out along said guide carrier 25, (transversely with respect to the main slide 6) properly positioning the grinding wheel 40 with respect to the bottom of the groove 1 of the feed wheel 2. Said grinding wheel carrier 39 is provided with a rib 50 having undercut edges fitting in undercut jaws 51 in a slide member 52 slidable on said rib 50. Said slide is provided with a circular recess 53 into which extends the circular hub portion 54 of a head 55 that serves as a mounting for a cross slide 56 in which is secured a diamond tool 57 for 45 dressing the surface of the grinding wheel. Mounted in a recess in the back face of the slide 52 is the enlarged head 58 of a screw 59 whose threaded portion extends into the threaded bore of said hub portion 54 of said head 55. 50 The projection of said end member 46 of the grinding wheel carrier 39 opposite the portion containing the slot 47 is provided with a hole 60 through which extends the reduced unthreaded neck portion of a screw 61 whose threaded end extends into said slide 52, thus making it possible to move said slide 52 longitudinally of said grinding wheel carrier 39. 60 Said slide 52 is provided with projecting lugs 62 through each of which extends a screw 63 that abuts against a projecting portion 64 of said head 55. Thus by turning said screws 63, said head 55 may be turned in 65 said slide 52 to vary the angular position of

said diamond tool cross slide 56 relative to the grinding wheel. The diamond tool 57 is mounted in a recess in said carrier 56 and is held in desired position by means of a screw 65. 70

Said head 55 is provided with a projection 66 through which extends the reduced neck portion of a screw 67 that is provided with a handle 68 for turning it. Said screw 67 extends into a threaded hole in said diamond 75 tool carrier 56, whereby the carrier may be moved on its slideway 69.

The tool is prepared for use by adjusting the guides 37 so that said guides properly engage groove walls, and adjusting the grinding wheel carrier 39 by means of its adjusting screw 48. The angular position of the guide carrier 25 and of the grinding wheel carrier 39 may be adjusted by turning said head 14. After the grinding wheel 40 and the guides 37 have been separately adjusted, the two may be moved as a unit by turning the handle 28. The slide 6 carrying the entire mechanism may be moved endwise along the gib 5 and the feed wheel 2 turned so that 90 two groove walls are properly engaged by the guides 37. Then the rotation of the feed wheel will carry the tool with it along the groove, causing the grinding wheel to grind the bottom of the groove 1. 95

When the grinding wheel 40 is worn, or when it is desired to dress its grinding surface to a different shape, the diamond tool 57 may be moved back and forth across the grinding surface of the grinding wheel as the 100 grinding wheel is rotated. The back and forth movement is obtained by turning the handle 68 of the screw 65 that moves the diamond tool carrier 56, and any desired adjustment of the diamond tool and carrier may 105 be obtained by turning the diamond tool head 55 by means of the screws 63 or by moving the slide 52 by means of its adjusting screw.

The above described dressing tool has numerous advantages. It may be very delicately adjusted to any particular lead or pitch of groove, depth of groove or diameter of feed wheel; and by removing the grinding wheel and guides and replacing them with 110 new ones, the tool may be used for any desired width of grooves and so on. The grinding or dressing operation is practically automatic, it being necessary only to move the guides into engagement with walls of the 120 feed wheel groove, the tool being then fed along the feed wheel by the rotation of the latter.

Obviously numerous changes may be made without departing from the invention and I 125 do not wish to be limited to the precise constructions shown.

What I claim is:

1. A device for dressing the grooves of helically grooved wheels and the like com- 130

prising a slide arranged to move across the face of the wheel, a rotatably mounted grinding wheel supported from said slide, and a guide supported from said slide and having portions adapted to engage groove walls to propel the slide and grinding wheel across the face of the wheel.

2. A device for dressing the grooves of helically grooved wheels and the like comprising a slide arranged to move across the face of the wheel, a rotatably mounted grinding wheel supported from said slide, and a guide supported from said slide and adapted to engage the wall of a groove to propel the slide and grinding wheel across the face of the wheel.

3. A device for dressing the grooves of helically grooved wheels and the like comprising a slide arranged to move across the face of the wheel, a rotatably mounted grinding wheel supported from said slide, a guide supported from said slide and adapted to engage the wall of a groove to propel the slide and grinding wheel across the face of the wheel, and means for adjusting the angular position of said guide and grinding wheel.

4. A device for dressing the grooves of helically grooved wheels and the like comprising a slide arranged to move across the face of the wheel, a rotatably mounted grinding wheel supported from said slide, a guide supported from said slide and adapted to engage the wall of a groove to propel the slide and grinding wheel across the face of the wheel, means for adjusting the angular position of said guide and grinding wheel, and means for adjusting said guide and said grinding wheel independently of each other.

5. A device for dressing the grooves of helically grooved wheels and the like comprising a slide arranged to move across the face of the wheel, a rotatably mounted grinding wheel supported from said slide, a guide supported from said slide and adapted to engage the wall of a groove to propel the slide and grinding wheel across the face of the wheel, means for adjusting the angular position of said guide and grinding wheel, means for adjusting said guide and said grinding wheel as a unit toward and each other, and means for moving said guide and said grinding wheel as a unit toward and from the work.

6. A device for dressing the grooves of helically grooved wheels and the like comprising a gib having beveled edges, a slide having an undercut rib fitting over one of said edges, a wedge block adjustably secured in said slide and fitting the other beveled edge of said gib, a rotatably mounted grinding wheel supported from said slide, and a guide supported from said slide and adapted to engage the wall of a groove to propel the

slide and grinding wheel across the face of the wheel.

7. A device for dressing grooves in a wheel or the like comprising a slideway, a slide movable therealong, a head adjustably secured to said slide, slideways in said head disposed transversely with respect to said slide, a carrier mounted in said slideways in said head, said head having a cross member disposed over the ends of said slideways, a rod mounted to rotate in said cross member, an operating handle for said rod, the end of said rod being screwthreaded and extending into a threaded hole in said carrier, whereby said carrier may be moved in said slideways, a guide adjustably mounted on the end of said carrier and adapted to engage the wall of a groove, slideways in said guide carrier, a second carrier mounted in said slideways, a grinding wheel mounted in said carrier, and means for moving said grinding wheel carrier in its slideways.

8. A device for dressing grooves in a wheel or the like comprising a slideway, a slide movable therealong, a head having a circular hub portion disposed in a circular recess provided therefor in said slide, said head having arcuate slots in which are disposed the shanks of screws whose ends are screwed into said slide to hold said head in desired angular position on said slide, slideways in said head disposed transversely with respect to said slide, a carrier movably mounted in said slideways in said head, a guide adjustably mounted on the end of said carrier and adapted to engage the wall of a groove, means for moving said guide carrier, slideways in said guide carrier, a second carrier mounted in said slideways and a grinding wheel mounted in said carrier.

9. A device for dressing grooves in a wheel or the like comprising a slideway, a slide movable therealong, a head having a circular hub portion disposed in a circular recess provided therefor in said slide, said head having arcuate slots in which are disposed the shanks of screws whose ends are screwed into said slide to hold said head in desired angular position on said slide, the hub portion of said head having an annular peripheral rib disposed in an annular groove provided therefor in said slide, slideways in said head disposed transversely with respect to said slide, a carrier movably mounted in said slideways in said head, a guide adjustably mounted on the end of said carrier and adapted to engage the wall of a groove, means for moving said guide carrier, slideways in said guide carrier, a second carrier mounted in said slideways, and a grinding wheel mounted in said carrier.

10. A device for dressing grooves in a wheel or the like comprising a slideway, a slide movable therealong, a head having a circular hub portion disposed in a circular recess provided therefor in said slide, said head hav-

ing arcuate slots in which are disposed the shanks of screws whose ends are screwed into said slide to hold said head in desired angular position on said slide, the hub portion of 5 said head having an annular peripheral rib disposed in an annular groove provided therefor in said slide, said slide having a hole therein, a plug in the inner end, said hole engaging said peripheral rib, a screw in the 10 outer end of said hole holding said plug firmly against said peripheral rib, slideways in said head disposed transversely with respect to said slide, a carrier movably mounted in said slideways in said head, a 15 guide adjustably mounted on the end of said carrier and adapted to engage the wall of a groove, means for moving said guide carrier, slideways in said guide carrier, a second carrier mounted in said slideways, and a 20 grinding wheel mounted in said carrier.

11. A device for dressing grooves in a wheel or the like comprising a slideway, a slide movable therealong, a head secured to said slide, slideways in said head disposed 25 transversely with respect to said slide, a carrier movably mounted in said slideways in said head, a guide adjustably mounted on the end of said carrier and adapted to engage the wall of a groove, means for moving said 30 guide carrier, slideways in said guide carrier, a second carrier mounted in said slideways, a grinding wheel mounted in said carrier, slideways on said grinding wheel carrier, a slide mounted therein, a head mounted in said slide, means for adjusting the angular 35 position of said head, a cross slide mounted on slideways provided therefor on said head and a dressing tool for said grinding wheel 40 mounted on said cross slide.

12. A device for dressing grooves in a wheel or the like comprising a slideway, a 45 slide movable therealong, a head secured to 50 said slide, slideways in said head disposed transversely with respect to said slide, a carrier movably mounted in said slideways in said head, a guide mounted on the end of said carrier and adapted to engage the 55 wall of a groove, means for moving said guide carrier, slideways in said guide carrier, a second carrier mounted in said slideways, a grinding wheel mounted in said carrier, slideways on said grinding wheel carrier, a slide mounted therein, a head mounted in said slide, means for adjusting the angular 60 position of said head, a cross slide mounted on slideways provided therefor on said head and a dressing tool for said grinding wheel 65 mounted on said cross slide.
